(57) **CLAIM**

The ornamental design for a mat type controller, as shown and described.

DESCRIPTION

FIG. 1 is a perspective view of the front, top and right side of a mat type controller showing my new design;

FIG. 2 is a top plan view thereof;

FIG. 3 is a front view thereof;

FIG. 4 is a left side view thereof;

FIG. 5 is a right side view thereof;

FIG. 6 is a rear side view thereof;

FIG. 7 is a bottom view thereof;

FIG. 8 is a perspective view of the front, top and right side of a mat type controller according to a second embodiment showing my new design;

FIG. 9 is a top plan view thereof;

FIG. 10 is a front view thereof;

FIG. 11 is a left side view thereof;

FIG. 12 is a right side view thereof;

FIG. 13 is a rear side view thereof; and,

FIG. 14 is a bottom view thereof.
